UNITED STATES PATENT OFFICE.

CHARLES A. ELIGH, OF DETROIT, MICHIGAN, ASSIGNOR TO LONG MANUFACTURING COMPANY, OF DETROIT, MICHIGAN, A CORPORATION OF MICHIGAN.

TOOL FOR PERFORATING CORRUGATED MATERIAL.

1,228,655.

Specification of Letters Patent.

Patented June 5, 1917.

Application filed November 4, 1915. Serial No. 59,531.

To all whom it may concern:

Be it known that I, CHARLES A. ELIGH, a citizen of the United States, residing at Detroit, in the county of Wayne and State 5 of Michigan, have invented certain new and useful Improvements in Tools for Perforating Corrugated Material, of which the following is a full, clear, and exact description.

In my co-pending application, S. N. 17852, 10 I showed a radiating fin formed from a flat straight strip of metal and curved in its own plane by corrugation, the corrugations diminishing in depth from one edge toward the other. In my co-pending application S. N. 45285, I describe the method of making 15 said fins, one step of the method being that of perforating the fin after it has been corrugated. As shown in said applications the perforations are placed indiscriminately 20 with reference to the corrugations. For example, in S. N. 17852 the apertures 26 are oval and cross corrugations more or less. It is evident that to form these apertures without flattening or otherwise distorting the 25 corrugations, which would probably result in changing the curvature of the fin, it is necessary to support the metal and retain it in its corrugated state while the metal is pierced. For this purpose I have designed 30 the novel tool shown in the accompanying drawings, in which:

Figure 1 is an elevation with a small portion broken away at one point.

Fig. 2 is a plan of the lower portion of 35 the tool; *i. e.*, the portion seen below line 2-2 in Fig. 1.

Fig. 3 is a sectional view on line 3-3 Fig. 1.

Fig. 4 shows a fin after it has been 40 perforated, and shows indiscriminate relationship between the corrugations and perforations. The converging lines may be taken to indicate corrugations. That is, each line may be considered the bottom of a corruga- 45 tion.

Fig. 5 is a modification in which the punch merely pierces the metal, the displaced metal remaining as a bur around the edge of the aperture.

50 Similar numerals refer to like parts in all of the views.

Upon the base 10 a stripper plate 11 is mounted upon compression springs 12. The desired number of punches 13 are fixed in

the base and extend upward through holes 55 in the stripper plate, the ends of the punches being below the upper surface of the plate when it is in normal position as in Figs. 1 and 3. A top plate 14 is placed above the stripper plate and is connected to, 60 or rather held in position with reference to the base by guide pins 15 which slide up and down in holes 16 in the base. A die 17 is secured to the under side of the top plate. In fact it is preferable to have the die and 65 top plate integral, and the drawings show this construction. The die is provided with apertures to register with the punches, said apertures extending through the top plate as well. It is understood, of course, that 70 this tool is placed in a punch press, which, being an article in ordinary use need not be illustrated. The base 10 is secured to the bed of the press and the top plate to the ram which is arranged to reciprocate per- 75 pendicularly to the bed.

The face of the die is corrugated just like the fin; that is it has corrugations complementary to those of the fin. The surface of the stripper plate is also corrugated. The 80 fin is laid upon the stripper plate, a frame 18 acting as a guide to locate the fin, and as the ram descends the die is brought down on the fin, the fin then being confined between the two corrugated surfaces. Continued 85 downward movement of the ram carries the top and stripper plates downward, the latter moving in opposition to the springs 12. As the punches are stationary the fin is forced down upon their ends, the corners of which, 90 being sharp and coacting with the sharp corners of the apertures in the die, act as shears and shear out pieces of the fin, thus forming the perforations seen in the fin in Fig. 4. As the fin is confined between the 95 two corrugated plates it is not distorted, and the edges of the apertures are left smooth and regular. As the die rises the springs force the stripper plate to follow it keeping the fin confined until the punches have been 100 entirely withdrawn from the fin. When the stripper reaches its limit of movement it comes to rest and the die continues upward, releasing the fin.

While the best results are obtained by 105 confining the fin between two corrugated plates, good results may be obtained with the die only corrugated, the stripper plate being

flat. Or, the flat stripper plate may have pins scattered over its surface to enter the fin corrugations and act as a sort of substitute for the corrugated surface. Another 5 modification is illustrated in Fig. 5 in which the punch 19 is pointed and does not shear the metal. In this method the metal displaced to form the aperture is not entirely removed but is carried up into the die in 10 the form of a bur 20, which remains on the fin after it is finished. The punch is slightly smaller than the hole in the die to leave room for this bur. Other modifications might be 15 made by a skilled mechanic assisted by the instruction herein given.

What I claim is as follows:

1. A tool for perforating material, comprising a die whose surface has corrugations complementary to the corrugations of the 20 material to be perforated and having apertures located indiscriminately with reference to the corrugations; punches adapted to pass through the material, into said apertures, thereby perforating the material, and pressing 25 means independent of the punches for pressing the material against the die, said pressing means being constructed with auxiliary provisions for maintaining substantially invariable pressure during the entire

travel of said punches from the top to the 30 bottom of the corrugations.

2. A tool for perforating corrugated material, comprising a die whose surface has corrugations complementary to the corrugations of the material to be perforated and 35 having apertures located indiscriminately with reference to and extending over one or more corrugations indiscriminately the edges of said apertures being adapted to act as shears, and punches having edges to coöperate with the edges of the apertures and shear perforations in the material lying 40 upon the corrugated surface.

3. A tool for perforating corrugated material, comprising a die whose surface has 45 corrugations complementary to the corrugations of the material to be perforated and having apertures which extend over two or more corrugations; and punches adapted to 50 pass through the material into said apertures, thereby perforating the material.

In testimony whereof I affix my signature in the presence of two subscribing witnesses.

CHARLES A. ELIGH.
